Attorneys.

UNITED STATES PATENT OFFICE.

NELLIE FORSMAN MANSURE, OF CHICAGO, ILLINOIS.

BOLSTER OR PILLOW-ROLL SUPPORT.

1,395,506.

Specification of Letters Patent.

Patented Nov. 1, 1921.

Application filed April 1, 1920. Serial No. 370,582.

To all whom it may concern:

Be it known that I, NELLIE FORSMAN MANSURE, a citizen of the United States, residing at Chicago, in the county of Cook 5 and State of Illinois, have invented a new and useful Improvement in Bolster or Pillow-Roll Supports, of which the following is a specification.

This invention relates particularly to 10 means for supporting a bolster, or pillow-roll, of a bed when the bed is in use. Bolsters of the character referred to are commonly of the form of a hollow cylinder, which is of comparatively light weight, and 15 which has a cut-away longitudinal segment to enable the pillows to be inserted or housed in the bolster while the bed is in made-up condition. It is usual, in preparing the bed for occupancy, to remove the 20 bolster and stand it in an inclined position in a corner of the room. This is an unsatisfactory method of disposing of the bolster at night, both because it is unsanitary and because there is danger of the bolster either 25 tipping over or sliding along the floor and falling.

The primary object of the present invention is to provide a bolster-support which will serve effectively to hold the bolster in upright position when the bolster is not in use on the bed; and a further object is to provide a collapsible device of the character indicated which, when not in use, can be folded sufficiently to enable it to be 35 housed under the bed.

The invention is illustrated, in its preferred embodiment, in the accompanying drawing, in which—

Figure 1 represents an elevational view 40 of the improved bolster-support, in extended condition, a bolster supported in the device being shown brokenly; Fig. 2, an elevational view of the device in collapsed condition; Fig. 3, a broken elevational view 45 showing the lower end of the bolster; and Fig. 4, a broken vertical sectional view illustrating a modification of the collapsible bolster-support.

In the construction illustrated in Figs. 1 50 and 2, the invention is embodied in a collapsible container comprising a rigid upper cylindrical section 1; a rigid lower base-section 2; and a collapsible intermediate section 3. The section 1 may comprise annular rim-members 1^a, and 1^b, connected by wires 1^c in accordance with the ordinary

method of forming wire baskets. Thus, the member 1 is in the form of an openwork cylindrical member.

The base-section 2 comprises annular 60 frame members, or rims, 2^a, 2^b, 2^c and 2^d, and wirework 2^e, in the form of an open weave. The section 2 has a contracted intermediate portion which is encircled by the intermediate band 2^b. The rim 2^d is larger 65 than the rim 2^c, and is secured thereto by the wires 4. Thus, there is provided an expanded base for the bolster-support, and the base is preferably of a greater diameter than the body of the bolster-support, while 70 the constricted intermediate portion of the base-section 2 is of considerably less diameter than the body of the bolster-support, so as to afford a shoulder 5 upon which the lower end of the bolster 6 can rest, as indicated in Fig. 1.

The collapsible intermediate section 3 is formed of two sets of light metal strips 3^a and 3^b, which cross each other and are pivotally connected, forming a lazy-tong or 80 parallel link arrangement which permits collapsing in the manner illustrated in Fig. 2. It will be understood that the strips, or bars, 3^a and 3^b are suitably curved, and that they are sufficiently flexible to permit such 85 a change in curvature as may be necessary in moving from the collapsed position to the expanded position and vice versa. The section 3 may be held in the extended position by means of a link, or hook, 7, which 90 locks the device against collapsing. The strips 3^a have their upper ends extended and pivotally connected to a circular band 8 which is firmly united to the band 1^b of the upper section 1. The strips 3^b have their 95 lower ends extended and pivotally connected with the circular band 9 which is securely united to the upper rim 2^a of the base section 2. Thus, the construction described comprises a collapsible cylindrical basket 100 having a contracted portion near its lower end and having its base expanded to prevent the device from tipping easily.

In the use of the device, the bolster, after removal from the bed, is inserted in standing 105 position in the bolster-support, which may be located in a corner of the room. Usually, the bolster-support will be of somewhat larger diameter than the bolster, so that the bolster can lean slightly in the basket and 110 bear against the vertical walls at the corner of the room. The bolster-support, however,

will stand squarely upon the floor, and will not slide readily on the floor, so that the bolster will be securely held in standing position. When the bolster is in use upon the bed, the bolster-support can be collapsed in the manner illustrated in Fig. 2 and in this form can readily be stowed away under the bed.

In the modification shown in Fig. 4, the bolster-support comprises two telescoping sections, namely a base-section 10 and an upper section 11, each comprising suitable wirework. The section 10 is equipped outside the wirework, at suitable intervals, with vertical guide-rods 10^a. The upper section 11 is of slightly larger diameter than the lower section and is provided with a lower rim 11^a which is of somewhat less diameter than the body of the section 11 and which 15 embraces the vertical guide-rods 10^a. When the device is in extended condition, the ring 11^a engages recesses, or off-sets, 10^b, with which the guide-rods 10^a are provided near their upper ends. Thus, the upper section 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 to prevent the collection of dust. By means of the improved device, the bolster can be supported without coming into contact with the floor, and there is little danger of the bolster being tipped over and soiled or injured. In Fig. 3, the dotted lines 6^a indicate the cut-away or open portion of the bolster, where the bolster is of a construction to enable the pillows to be stowed away therein during the day time.

The foregoing detailed description has been given for clearness of understanding only, and no unnecessary limitation should be understood therefrom, but the appended claims should be construed as broadly as permissible, in view of the prior art.

What I regard as new, and desire to secure by Letters Patent is:

1. A bolster-support comprising a non-collapsible open wirework cylindrical upper section, a base section having a constricted intermediate portion adapted to serve as a support for the lower end of the bolster, and a collapsible intermediate section joined to the upper and lower sections.

2. A bolster-support comprising a non-collapsible open wirework cylindrical upper section, an open wirework base-section having a constricted intermediate portion and an expanded base end, and a collapsible intermediate section joined to the upper section and the base-section.

3. A bolster-support comprising a cylindrical upper section, a base-section having a constricted intermediate portion, and a collapsible intermediate section comprising sets of parallel bars pivotally joined together and pivotally connected with the upper section and the base section.

NELLIE FORSMAN MASURE.
